UNITED STATES PATENT OFFICE.

WILLIAM AKIN, OF LOS ANGELES, CALIFORNIA.

WATER-FILTER.

No. 830,277.

Specification of Letters Patent.

Patented Sept. 4, 1906.

Application filed February 9, 1906. Serial No. 301,280.

To all whom it may concern:

Be it known that I, WILLIAM AKIN, of the city of Los Angeles, in the county of Los Angeles and State of California, have invented 5 certain Improvements in Connection with Water-Filters, of which the following is a full, clear, and exact description or specification, reference being had to the annexed drawings and to the letters marked thereon.

10 This invention has reference to that class of filters which are used upon the discharge-mouths of water-taps or, as they are sometimes called, "faucets."

Upon the annexed drawings, Figure 1 is a 15 vertical section of a filter and its coupling constructed according to my present improvements. Fig. 2 is an elevation of the same corresponding to Fig. 1. Fig. 3 is an elevation of the filter-casing detached from the 20 coupling, showing the outwardly-flaring flange, also shown in section in Fig. 1. Fig. 4 is an elevation of the coupling and the flange and ring within which is the elastic ring against which the outwardly-flaring 25 flange on the upper end of the filter-casing presses when the filter-casing and the coupling are screwed together as shown in Figs. 1 and 2. Fig. 5 is a section of the coupling detached from the filter. Fig. 6 is a trans- 30 verse section, on an enlarged scale, of the perforated casing at the lower part of the filter-casing, as also shown on a smaller scale in Fig. 1. Fig. 7 is a plan corresponding to Figs. 1, 2, and 3.

35 In Figs. 1 and 2 the casing of the filter is marked A. It is formed of any suitable material of a non-corrodible character or may be formed of steel, brass, or other material plated with nickel or any metal which resists 40 corrosion.

As will be seen from Figs. 1, 2, and 3, the upper part of this casing is formed with a screw-thread, by which it is connected and screwed onto the exterior lower part of the 45 coupling B, which has a corresponding screw-thread formed externally upon the lower part of itself. The flaring flange C of the upper part of the filter-casing A when screwed tight upon the coupling B presses upward 50 and hard against the elastic packing-ring D and causes the packing-ring D to be compressed within the annular recess E, formed upon the lower part of the coupling B by the flange C' and the ring C'', so that when the 55 filter-casing A is screwed upward upon the lower screwed portion of the coupling B the

flaring flange C compresses the elastic ring D into the annular recess E, which always contains the elastic packing D under any pressure to which it is or may be subjected. By this 60 arrangement a perfectly water-tight connection is formed by means of the flaring flange C of the filter-casing, the flange C', the ring C'' and the annular recess E of the coupling B, and the elastic ring D, these parts being 65 tightly held in union by the filter-casing and holder being screwed together in the manner hereinbefore set forth.

While the filter-casing A is readily removable by unscrewing it from the coupling B, 70 the india-rubber or other elastic lining G, placed within the coupling B, is firmly held in its place so as to be incapable of being forced outward by the pressure of water flowing through the filter because of the upper part of the coupling B being turned 75 slightly over as an inwardly-contracting projection, and the coupling B is held in its place upon the nose of a tap or faucet by a cement of shellac dissolved in alcohol. The lower 80 part of the filter-casing is constructed of an upper perforated dome-shaped plate H and of a lower inverted-dome-shaped plate I, the two pieces being connected together by a flange J on the lower portion being turned upward 85 over and pressed upon an annular projection on the upper part, as shown at Fig. 6. The lower part of the filter-casing A, as shown at Fig. 1, is composed of one or more layers of compressed wool K, which rests immediately 90 upon the upper perforated dome H, above which a piece of sponge L is inserted. This piece of sponge becomes compressed within the filter-casing by means of the inwardly-projecting flange M at the lower part of the 95 connecting-piece B when the filter is screwed upon the coupling B.

I claim—

The combination consisting of the filter-casing, the filter-coupling, the lower part of 100 the filter-coupling being screw-threaded externally, the annular recess having its mouth opening downward at the upper end of the screw-thread of the coupling, the annular elastic packing-ring within the annular recess, 105 the filter-casing having its upper part screw-threaded to be screwed upward on the lower part of the coupling, the flaring end of the screwed upper part of the filter-casing 110 pressed by the tightening action of the screw on the coupling and filter-casing respectively, against the elastic packing-ring in the

annular recess of the coupling, the inwardly-turned flange at the upper end of the coupling for confining the elastic ring therein which provides for the filter being connected
5 with the mouths of water-taps by shellac cement, substantially as hereinbefore described.

In testimony whereof I have hereunto set

my hand and seal in the presence of two subscribing witnesses.

WILLIAM AKIN. [L. S.]
